Primary Examiner — Elizabeth J Oswecki*(74) Attorney, Agent, or Firm* — Seyfarth Shaw LLP(57) **CLAIM**

The ornamental design for the safe door, as shown and described.

DESCRIPTION

FIG. 1 is a perspective view of a safe door showing a new design;

FIG. 2 is a right side view thereof;

FIG. 3 is a top view thereof; and,

FIG. 4 is a front view thereof.

The broken lines illustrate environmental structure which forms no part of the claimed design.

All sides not shown form no part of the claimed design.
